UNITED STATES PATENT OFFICE.

ALBERT O. PRICE, OF COSHOCTON, OHIO.

DESIGN FOR A PEDESTAL-MOUNTED RADIOPRODUCER.

Application filed December 24, 1925. Serial No. 15,847. Term of patent 14 years.

To all whom it may concern:

Be it known that I, ALBERT O. PRICE, a citizen of the United States of America, residing at Coshocton, in the county of Coshocton and State of Ohio, have invented a new, original, and ornamental Design for a Pedestal-Mounted Radioproducer, of which the following is a specification, reference being had to the accompanying drawing, forming a part thereof.

The figure is a perspective view showing the ornamental design of the pedestal mounted radio reproducer.

I claim:

The ornamental design for a pedestal mounted radio reproducer as shown.

ALBERT O. PRICE.
